UNITED STATES PATENT OFFICE.

FREDERICK WILLIAM VARLEY, OF KINCAID, SASKATCHEWAN, CANADA.

SHEAF SHOCKER.

Application filed June 3, 1922; Serial No. 565,738, and in Canada April 16, 1920.

This invention relates to sheaf shockers, particularly to those of the type in which the sheaves are suspended immediately previous to the dumping operation.

Other objects are to provide means whereby the basket will be intermittently rotated so that on a complete revolution of the same the basket would be filled and the shock completed, to provide means whereby on the basket being filled with sheaves, the same will be disengaged and thereby come in a position to dump the shock. Further objects are to provide a track on the shocker on which the basket is adapted to rotate to be brought into dumping position, to provide means to rotate the basket over the track to bring the same into dumping position. Further objects are to provide moving elements slidably mounted within a receiving frame and designed to be moved longitudinally, to provide a connection between the moving element and a pivotally mounted member on the basket, and to provide a driving connection between the moving element and a motor carried by the shocker. Further objects are to provide a resilient means whereby on the shock being formed in the basket the moving element will be brought into motion, to provide means co-acting with the rotation of the basket whereby the moving element will be moved longitudinally and subsequently brought to a resting position.

Further objects are to provide a conveying device designed to deliver the sheaves into the basket, to provide a guiding means on the conveying device whereby each sheaf will be guided into its proper position in the basket which rotates on every sheaf being delivered into it, thus allowing the shock to be formed on the complete rotation of the basket. A further object is to provide a means whereby the guiding element will be raised on the dumping operation of the basket in order to clear the way for the same. Still further objects are to provide a means at the bottom end of the conveyor to raise or lower the same, to provide a moving driving shaft feeding motion to the conveyor and to provide a means of holding the shaft in working position. Further objects are to provide a device located underneath the basket and designed to collect the grain loosened from the sheaves falling into the basket. Further objects still are to provide an improved grain shucker that is

simple in construction and generally to adapt the several parts thereof to better perform the functions required of them.

In the drawings;

In the drawings, like characters of reference indicate corresponding parts in all the figures.

Referring to the drawings, A represents the improved grain shocker comprising a platform 10 inclined forwardly and carried at its forward end on a triangular truck 11 having its rear wheels 12 slightly larger in diameter than the forward castor wheel 13. The rear end of the platform 10 is carried by the wheels 14 of slightly larger diameter than the wheels 12, thus retaining the platform 10 in an inclined position. The platform is adapted to carry in the rear thereof a pair of double tracks 15 comprising a lower inner track 16 and an upper and slightly outer track 17. The tracks 16 and 17 are formed with the rear end 18 curved downwardly and designed for a purpose that will be hereinafter made clear. The platform 10 carries a basket 19 circular in cross section and tapering downwardly. The basket 19 is reinforced by means of a frame 20 engaging the upper end thereof and also by means of a second frame 21 engaging the outer face of the basket adjacent its lower end. The two frames 20 and 21 are fastened on their sides to the spokes of a pair of wheels 22 and 23 which are mounted on the lower track 16. The wheels 22 and 23 are formed on the hubs thereof with pintles 24 designed to carry rollers 25 and 26 engaging the lower face of the upper track 17; thus locking the basket and wheels in sliding position within the tracks 16 and 17. The lower frame 21 is not fastened to

the gasket by any means, but merely surrounds the same to support it whereas the upper frame 20 is fastened to the upper edge of the basket by means of clamps 27. The clamps 27 are each formed with a casing 28 carried by the frame 20 and each casing 28 carries a pintle 29 on which is loosely mounted a roller 30 on which rests the upper edge of the basket 19, as clearly shown in Figure 12 of the drawings.

The platform 10 is formed underneath the basket 19 with a grain pan 31 tapering rearwardly and formed on its forward part with a sliding door 32 through which the grain falling from the basket 19 and gravitating down the pan 31 may be removed. The lower end of the basket 19 is formed on its outer periphery with teeth, thus providing a gear 33 which meshes with a gear 34 carried by a small standard extending from the platform 10 and carrying on its under face a finger 35 designed for a purpose that will hereinafter be made clear. The top face of the gear 34 is formed with an inner circular toothed track 36 and an outer concentric toothed track 37, the inner of which tracks is designed to mesh with a gear 38, carried by a transverse shaft 39 journalled in a bearing formed on the end of an arm 40 fastened to the platform 10. The shaft 39 carries one of the members 41 of a jaw clutch which is designed to engage the second member 42 thereof carried by a second shaft 43 fastened on an axis in alignment with that of the shaft 39 and slidably mounted in the arm 44 fastened to the platform 10, the shaft 43 carrying the second member of the clutch 42 may be a telescoping shaft, or may otherwise be loosely mounted in the arm 44 to slide the member 42 in and out of engagement with the clutch member 41 by means of the following mechanism.

The member 42 of the clutch is formed integral with a pulley 45 carrying on its interior a hollow spiral spring 46 having one end fastened to a peripheral point 46^a and the opposite end fastened to the shaft 43. Coiled around the shaft 43 and bearing against the arm 44 and the outer face of the pulley 45 is a coil spring 47 pressing clutch member 42 into engagement with the other member 41 of the jaw clutch. In the groove of the pulley 45 is fastened as at 48 one end of the flexible element 49 coiled around the same and extending forwardly of the shocker, engaging a roller 50 carried on the platform, a second roller 51 also carried by the platform and thence turning at right angles and being connected to the knotter mechanism 52 carried by the binder deck 53. By means of this arrangement, it will be seen that at every sheaf being knotted and delivered to the conveyor a pull will be exerted on the flexible ele- 130

ment 49 which will rotate the pulley 45 rearwardly thus tensioning the coil spring 46 and allowing the spring 47 to throw the clutch member 42 into engagement with the clutch member 41 and thus allow the shaft 39 and pinion 38 to rotate the gear 34 which will in turn rotate the basket 19 by means of the gear 33 to a predetermined extent until the knotter 52 releasing the flexible element 49 will allow the spring 46 to rotate the pulley 45 to its former position until another sheaf is delivered from the binder deck 53 when the same operation will be repeated.

The forward end of the platform 10 is provided with a frame 54 preferably rectangular in shape and it is supported by means of the members 55 fastened to the platform 10 as shown at 56. Slidably mounted within the rectangular frame 54 is a moving element 57 of oblong formation and provided on its inner periphery with a toothed race 58 which in cross section extends only one-half the width of the element 57. Also mounted within the moving element 57 is a second race 59 in concentric relation to the toothed race 58 also extending in width only one-half the element 57. The moving element 57 is formed with a shank 60 carrying an eye 61 in engagement with a bale 62 pivotally carried by the pintles 24 of the basket 19. Mounted adjacent the rear end of the frame 54 is a transverse shaft 63 over which is telescoping another shaft 64 as shown in figures 8 and 9 of the drawings. Rigidly mounted on the shaft 63 is a pinion 65 in mesh with the toothed race 58 of the moving element while a roller 66 loosely mounted on the shaft 63 engages with the inner face 59 of the element 57. The telescoping shaft 64 carries at one end the female member 73 of a friction clutch 74 and the member 73 is integrally formed with the shaft 64. The shaft 64 is provided, adjacent the clutch member 73 with an annular rib or flange 68 and loosely mounted over this, rib is a ring or collar 69, L-shaped in cross section. This ring 69 is loosely retained over the shaft 64 and rib 68 by means of a washer 70 carried by the ring and loosely engaging the shaft 64 and rib or flange 68. The shaft 63 is formed with two diametrically opposite longitudinal grooves 71 which are engaged by two diametrically opposite longitudinal ribs 72 formed within the hollow shaft 64 whereby when the shaft 64 is rotated the shaft 63 will also turn therewith. By means of the ring 69 and washer 70 being provided and loosely mounted over the flange 68, it will be obvious that although the shafts 63 and 64 will be turning, the collar 69 loosely mounted on the shafts may be held rigidly and thus not hinder the movement of the shafts. A second shaft 75 mounted on an axis in alignment with that of the shaft 63 carries

the male member 76 of the clutch 74 and the shaft 75 journalled in suitable bearings 77 and carried by the platform 10 is provided with a pulley 78 which has a belt connection 79 with a pulley 80 carried on the shaft 81 of a motor 82 suitably positioned on the platform 10. Coiled around the shaft 64 and bearing against the side wall of the frame 54 is a coil spring 83 which also bears against the ring 69 adjacent the friction clutch 74 and the same is designed to press the clutch member 73 into engagement with the clutch member 76 in order that the motion imparted to the clutch member 76 by the motor 82 may be transmitted to the pinion 65. It will thus move the movable element 57 in longitudinal direction. The forward supporting element 55 pivotally carries an arm 84 which is formed at its upper end with an eye 85 engaging one end of the flexible member 86 which extends along the rectangular frame 54 and engages a roller 87 carried on top of the same and thence extends to a second roller 88 carried by an arm 89 extending from the top of the frame 54 thence to a third pulley 90 carried by an arm 91 also extending from the frame 54 and from which roller 90 the end of the flexible element 86 is fastened to an eye 92 formed on a yoke 93 extending from a rectangular frame 54 and having its two arms converging to points diametrically opposite on the collar 69 previously described and fastened thereby by means of clamps 94. The opposite end of the arm 84 engages one end of the flexible element 95 and the element 95 extends forwardly and engages a pulley 96 mounted in a slot formed in the forward supporting member 55 and thence extends rearwardly passing through a slot 97 formed in the rearward supporting member 55 and having its end 98 fastened to the end of an arm 99 pivotally carried by a stud 100 extending from the platform 10. The arm 99 is of sufficient length to extend adjacent the finger 35 located underneath the gear 34 and previously referred to. The arm 84 intermediate of its fulcrum point and its upper end is pivotally connected to a rod 101 extending through the end wall of the frame 54 and carrying at its outer end a plate 102. Coiled around the rod 101 and bearing against the plate 102 and the end wall of the frame 54 is a coiled spring 103 designed to press the plate 102 rearwardly against the moving element 57 and thereby hold the arm 84 in an approximately upright position. The flexible element 95 is fastened intermediate of its length to an eye formed on a retaining member 104 formed at its outer end with hooks 105 engaging the bale 62 and the retaining member 104 is pivotally carried by an arm 106 fastened to the rear end of the rectangular frame 54. When the revolution of the basket 19 is

completed and the finger 35 carried by the gear 34 is thus brought into engagement with the rod 99, the same is tripped by the finger 35 and will thus exert a pull on the flexible member 95 which will pivot the retaining member 104 on its pivots provided on the arm 106 and thus disengage the hooked ends 105 from the bale 62 of the basket. Simultaneously with this movement, the flexible member 95 will pull on the lower end of the arm 84 and bring the same into upright position while releasing the pressure on the spring 103 coiled around the rod 101 and connected to the arm 84 and the plate 102 will thus be forced against the end of the movable element 57 thus starting its forward movement while the upper end 85 of the arm 84 being brought rearwardly the flexible member 86 being released will itself release the yoke 93 retaining the clutch member 73 from engagement with the clutch 76 and on the same being released the spring 83 will force the two members of the friction clutch 74 together. On this engagement of the clutch members, motion will be transmitted from the motor 82 to the pinion 65 which will thus rotate, and being in engagement with the toothed race 58 of the moving element 57 will move the same longitudinally and as the same is in engagement with the bale 62 of the basket, the element 57 will move the basket and wheels 22 and 23 along the tracks 16 and thus rotating the basket over the same will bring it on the curved ends 18 into dumping position. As the moving element 57 is oblong in form and the toothed race 58 extends all around the same, the pinion 65 will be caused to engage with the lower portion of the toothed race 58 and thus cause the return movement of the moving element 57 thereby withdrawing the basket 19 to its normal position. When the moving element 57 is brought back to normal position, the end of the same will engage the plate 102 of the bumper and pushing the pivoting arm 84 back into normal position the upper end 85 of the arm 84 will pull on the flexible member 86 and thus withdrawing the yoke 93 will disengage the two members of the clutch 74 thus bringing the pinion 65 to a stop and the flexible member 95 being released will also allow the fastening member 104 to pivot on its pivot points 106 and bring the hooked ends 105 thereof into engagement with the bale 62 of the basket which is thus in a position to receive the sheaves delivered thereto from the deck of the binder. Carried on the platform 10 adjacent the binder deck 53 is a conveyor 107 formed of a lower portion 108 and an upper and inclined portion 109. The two portions 108 and 109 are formed at their adjacent ends with shafts 110 and 111 as shown in Figure 24 which carry on their ends gears 112 and 113 which

both mesh with the third gear 114 keyed on a sleeve 115^a loosely mounted on a crank shaft 115 which extends beneath the conveyors 108 and 109. The shafts 110, 111 and 115 are carried by an adjustable tie-frame E 70 which consists of sliding members 170 and 171 and other sliding members 172 and 173 carried at right angle to the former sliding members. The sliding members are provided with a series of threaded perforations 75 174 designed to be engaged by set screws or bolts 175 and 176 adapted to secure the sliding members in a predetermined adjusted position. The sleeve 115^a mounted on the crank shaft 115 carries at its outer ends a 80 sprocket 116 which is keyed thereon. The sleeve 115^a is loosely held in position on the crank shaft 115 by means of pins 115^b. The sprockets 116 are each connected by means of a sprocket chain 117 to a sprocket 118 85 carried by a shaft 119 which carries a pulley 120 connected by means of a belt 121 to a pulley 122 provided on the shaft 75. By means of this arrangement, the continuous motion is fed to the conveyors 108 and 109 from the motor 82 located on the platform of the shucker. The crank shaft 115 is provided on each of its outer ends with a pinion 123 keyed or otherwise secured thereon. Each of the pinions 123 meshes with an arcuate 90 rack 124 suitably fastened to the platform 10 while a resilient arm 125 engages the upper side of the shaft 115 and holds the same in the desired position.

Pivots mounted on each end of the 100 shaft 119, are frames 126 which are also pivotally connected to the crank shaft 115 and each is formed with an arm pivotally carrying a dog 127 which engages with the pinion 123 in order to lock the same in position and the dog 127 is normally held in engagement with the pinion 123 by means of a spring 127^a. The arcuate rack 124 is formed on the side with a groove 124^a and is also provided on the under face with an 110 under groove in which travels a roller or castor 126^a, the castor 126^a being pivotally carried by the frame 126. The latter frame is also formed with a projection pivotally carrying a guide block 126^b which travels 115 along the groove 124^a on the side of the arcuate rack 124. It will be obvious that as the shaft 115 travels along the rack 124 through the engagement with the latter of the pinion 123, the frame 126 will also travel 120 in radial alignment with the shaft, since it is freely connected to the same. In order to provide an even smooth movement of all the parts, the arcuate rack 124 is formed as an arc of a circle, the centre of which would be 125 the shaft 119, and as all the elements travelling along the rack 124 are pivoted on the fulcrum 119, it is obvious that the parts will evenly move as the radius of a circle around its centre.

The frames 126 intermediate of their length are each provided with a crank spindle 126^a, the crank of which extends outwardly of the frame, while its inner end on the inner side of the frame carries a bevelled gear 128.

The bevelled gear 128 is designed to mesh with a bevelled gear 129 carried by a vertical spindle 129^a which is journalled in an arm 129^b extending inwardly of the frame 126 and rigidly connected thereto.

The vertical spindle 129^a is designed to be supported at its upper end by means of a collar formed at the end of an arm 129^c carried by the frame 126, and extending inwardly thereof. Each of the vertical spindles 129^a is provided intermediate of its length with a pulley 130 and 130^a rigidly connected thereto and adapted for a purpose 20 which will presently be made clear.

The opposite end of the shaft 119 is equipped with a similar frame 126 similarly arranged to that just described and of which a further description is not believed necessary and which is shown in Figure 25.

The dog 127 as shown on the right side of Figure 25 is formed at its upper end with a ring which engages the end of a flexible element 131 which extends obliquely downwardly through a transverse orifice in a crank spindle 126^c. The flexible element 131 is retained in the orifice of the spindle 126^c through any suitable means preferably by being knotted on each side of the spindle as shown at 130^b on Figure 26. The flexible element 131 as shown in Figure 25 then extends downwardly of the spindle 126^c engages a small pulley or an eye 132 and the end of the flexible element extends across the platform 10 of the machine and is fastened to the groove of the pulley 130^a, provided on the opposite frame 126.

The flexible element fastened to the dog 127 in engagement with the opposite pinion 45 123 shown on the left of Figure 24 at the opposite end of the crank shaft 115 is similarly connected to the parts of the second frame 126 and extends across the platform 10 to be engaged at its end with the pulley 50 130 of the frame 126 shown at the right in Figure 25 of the drawings.

It will be obvious that by means of this arrangement when the crank spindles 126^c are manipulated, the flexible element 131 being attached to the spindle 126^c by means of the knots 130^b, the said element will be wound around the spindle 126^c and thus pull on the upper end of the dog 127 and causing the same to fulcrum on its pivot, will disengage it from the teeth of the pinion 123.

The tightening screws of the T-frame E are then loosened and the crank shaft 115 operated in order to raise or lower the conveyors 108 and 109 to the desired level,

when the tightening screws 175 and 176 are again tightened, and the dog 127 allowed to be forced back in engagement with the pinions 123 in order to lock the same on the rack 124.

It will be understood that there are two flexible elements 131, one for each of the frames 126 and that the elements 131 extend across the platform 10 to the pulley 130 of the opposite frame 126.

In construction, it is desirable to have the rack 124 made on an even radius having the shaft 119 as its centre. As this shaft 119 carries a sprocket 118, which is connected through the sprocket chain 117 to the sprocket 116 carried by the sleeve 115 mounted on the crank shaft 115, the chain 117 will always retain its tension between the sprockets 116 and 118.

The upper end of the conveyor 109 is provided with a guiding means B, which comprises a skeleton frame 136 the sides of which are suitably hinged to the back thereof and are provided with canvas or sheet metal as desired and the top of the skeleton frame 136 is provided with suitable spring

hinges 137 engaging the plates 138 which are designed to engage the sheaf when the same is delivered from the conveyor 109 and direct the same with the butt end upward

into the funnel formed by the skeleton frame 136 into the basket 19 which will subsequently be rotated slightly in order to bring over an empty space underneath the skeleton frame 136. The two lower arms or rods

139 of the skeleton frame 136 are formed with a projection 140 having a chisel-like forward end and which engages with the member 141 pivotally carried by a buckle 142 formed in an arm 143 of the frame 144.

The frame 144 consists of two arms 143^a carrying a sheet metal member 145 which extends between them. Extending across the sheet metal member 145 and rigidly attached to arms 143^a are a plurality of tubular members 146 through each of which extends a spring 147 fastened to the arms 143, which extend parallel to the arms 143^a.

Through this arrangement the arms 143^a and the member 145 carried thereby are resiliently secured to the arms 143. The springs 147 are fastened to the arms 143 by means of hooked ends 148.

The upper ends of the arms 143 are provided with elbows 149 which carry rods 150 extending at right angles to the arms 143 and of approximately the same length as the latter. The buckles 142 provided in the arms 143 carry two arcuate arms 151 carried thereby by means of the pintle 152, the upper end of the arcuate arms 151 are formed with pintles 153 extending outwardly and engaged in recesses provided in the buckles 142. The pintles 153 also engage the member 141 previously described and which

is rigidly connected to the projection 140 on the rod 139.

A spring 154 is provided which is connected to the pin 152 at one end and has its outer end connected to the member 141. As the sheet metal member 145 serves as a covering for the funnel member 136, the hinged member previously described and provided in the buckles 142 is provided for the purpose of turning the L-shaped member shown in Figure 17, when the basket 19 is rotated to a dumping position. The upper edge of the basket 19 is designed to hit the lower end of the member 144 and thus pivot the same upwardly at the same time bringing the arm 150 downwardly. When the basket 19 is returned to normal position, its upper edge will strike the arm 150 and thus pivot the member 144 back into its normal position shown in Figure 15.

The guiding element B is pivotally secured to the upper end of conveyor 109 on each side thereof through a rod 9 and a rod 9^a, each pivotally connected at one end to the shank of the conveyor and each at the other end to a staple 8 or other suitable retaining element carried by the skeleton frame 136. A bearing block 7 is provided through which extends screw 6 operated by winged head 5. When the screw 6 is tightened, the lower end of the guiding element is forced away from the conveyor head and its inclination increased, whereas on the member 6 being unscrewed, the lower end of the guiding funnel draws nearer to the elevator head and assumes a practically vertical position.

By means of this arrangement, the alignment of the guiding element and the conveyors will be preserved when the latter are raised or lowered.

This grain shocker is attached stubble-ward of a binder (which may be by means of the arms 9 clearly shown in Figure 2 of the drawings). It may either be detachable from, or be formed integral with, the binder, and the draft thereof may be either with horses or tractor, and should be co-ordinated with that of the binder, when in use. As the sheaves are delivered from the binder deck 53 on to the conveyor 108, the knotting mechanism at every sheaf being delivered to the conveyor, actuates the basket through the flexible member 49 being withdrawn and thus bringing the clutch members 41 and 42 into engagement by overcoming the tension of the spring 46 provided on the pulley 45 as previously described. This engagement will be just long enough to allow the basket to be rotated the space occupied by a sheaf therein so that on the complete rotation of the basket, the same will be filled with sheaves and the shock thus formed in the basket 19. The clutch members 41 and 42 are brought out of en-

gagement by the knotter releasing the flexible member 49 which also releases the tension of the spring 46 of the pulley 45 which overcomes the pressure of the coil spring 47 and thus rotates the member 42 rearwardly out of engagement from the member 41.

The shaft 39 and pinion 38 are prevented from any rearward movement with the member 42 by means of ratchet 155 rigidly carried by the shaft 39 and engaged by a dog 156. When the basket 19 will have made a complete revolution, the finger 35 provided on the under face of the gear 34 will trip the arm 99 which pulling on the flexible element 95 will disengage the hooked ends 105 of the fastening member 104 from the bale 62 of the basket and will simultaneously liberate the bumper 102 from the pressure of the spring 103 and release by means of the flexible member 86 the yoke 93 which on being released will allow the member 73 of the friction clutch 74 to be pressed into engagement with the member 76 by means of the pressure of the spring 83 coiled around the telescoping shaft 64. Motion will thus be fed to the pinion 65 which will move the moving element 57 in a longitudinal direction rearwardly so as to carry the basket by means of the wheels 22 and 23 and the rollers 25 and 26 in engagement respectively with the lower track 16 and the upper track 17 to dumping position at the curved ends 18 of the tracks. The moving element will then be returned through the pinion 65 engaging the lower course of the toothed race 58 and the basket will thus be brought back into normal position when the forward end of the moving element 57 will engage the plate 102 of the bumper and overcoming the pressure of the spring 103 will pivot the arm 84 on its fulcrum and withdraw through the flexible member 86 the yoke 93 thereby disengaging the members 73 and 76 of the friction clutch 74 and bringing the pinion 65 to a stop, the lower end of the arm 84 of the same being pivoted on its fulcrum will pull on the flexible member 95 and thus pivoting the fastening member 104 on its pivots 106 will bring the hooked ends 105 thereof into engagement with the bale 62 of the basket and the member 95 will also bring the arm 99 into a straight position ready to be tripped again by the finger 35 on another revolution of the basket being completed. As the sheaves are delivered to the conveyor 108 the same will deliver them to the conveyor 109 which will deliver them through the guideway 136 into a proper position in the basket 19. The plates 138 will engage the heads of the sheaves and will deflect the same so that the head of every sheaf may fall downward into the basket 19. This is adapted so that when the basket is tipped over to dump a shock the butts of the sheaves will be down on the ground as it

is desired to have them fall from the shocker. On every dumping movement of the basket the L-shaped member 144 will be pivoted upwardly on the rearward trip thereof and on the basket being brought back to normal position the rods 150 will be tripped, thus bringing the member 144 back to normal position. The conveyors 108 and 109 may also be raised or lowered to the level of the binder deck by means of the arcuate racks, and the dogs locking the pinions 123 on the racks as previously described.

If desired an alternative means of rotating the basket 19 may be provided as shown in Figures 29, 30, 31 and 32 of the drawings. This improved means consists of an upright spindle 160 on which the gear 33 may be keyed. The gear 33 as previously described is designed to mesh with the gear 34 provided with the top toothed tracks 36 and 37, which are adapted to be engaged by the gear 38 mounted on the horizontal shaft 39. As this part of the mechanism is the exact replica of that already described, it is not believed necessary that the operation of the parts be further enlarged upon.

Mounted on the upper end of the spindle 160, is a pan or other shallow receiving member 161, the bottom of which may be formed of crossing ribs 162 as shown in Figures 30 and 31. As the lower end of the basket 19 is formed in the well known manner with the crossed ribs, pins could be provided on the crossed ribs 162 which would engage the ribs of the bottom part of the basket 19 and therefore cause the basket 19 to rotate whenever the pan 161 would be rotated by means of the movement imparted to the gear 33 by the gear 34.

The engaging means between the basket 19 and the pan 161 shown in the accompanying drawings consists of lateral projections 163 formed on the basket, which projections are designed to come into bearing engagement with lugs 164 provided on the inner periphery of the pan 161 as clearly shown in Figure 30 of the drawings.

When the basket 19 has been dumped and is being returned to normal position, the lower part thereof will fall into the pan 161, and the lateral projections 163 will each fall between two lugs 164. As the rotating movement imparted to the gear 33 by the previously described mechanism connected to the knotter of the binder is transmitted to the pan 161, the lugs 164 will be brought into bearing engagement with the lateral projections 163 of the basket, and will carry the basket around with the pan 161 to the predetermined extent, as regulated by the knotter mechanism of the binder.

Obviously this is only one of the several engaging means which could be provided for the basket 19 and several minor changes

as the one previously described could be made, which would fall within the scope of the invention.

In Figure 33 is shown a perspective view of the funnel-shaped guiding means, in which the sides are filled in with canvas or sheet metal and are spring held together through the spring hinges 137 and 137^a, also the rods 139 of the skeleton frame 136 are offset or bent inwardly as shown at 139^a in order to allow the rods 150 of the frame 144 to travel downwardly when the lower end of the frame 144 is struck by the edge of the basket 19, when the latter is being dumped.

Through this arrangement of the sides being resiliently held by means of spring hinges, it will be obvious that an abnormally large sheaf will not be retained by the upper end of the funnel and stop the working of the shocker, but will spread the sides of the funnel-shaped guiding means and will, as the smaller sheaves, fall through it and assume its position in the rotating basket 19.

Figure 34 shows an alternate form of funnel-shaped guiding means, in which the member 144 instead of being provided with the inner arms 143^a, and the sheet member 145 is formed of two panels or frames constructed of fabric or sheet metal 145^a, which are attached to the arms 143 through the spring hinges 145^b.

The remaining structure of the guiding means is of exactly the same construction as that shown and described in Figure 33 with the exception that the arms 139 instead of being offset or bent inwardly as shown at 139^a in Figure 33, are bent outwardly as shown at 139^b in order to provide a clearing space 139^c through which on its pivotal movement, the arms 150 of the member 144 will have clearance.

In order to permit this movement of the arm 150 the arm 143 is offset or bent outwardly immediately above the buckle 142. If it should be found more convenient, this offsetting or bending of the arm 143 may be dispensed with and the clearing space 139^c may be formed within the skeleton frame 136 instead of without as shown. If desired also and in order to reduce the length and size of the tracks 16 and 17, and the length correspondingly of the frame 54 and moving element 57, the basket 19 may be equipped with the dumping means illustrated in Figure 35. The wheels 22 and 23 are of a smaller diameter than those shown in Figure 1 of the drawings, and this allows the tracks 16 and 17 to be nearer to one another and thus reduces the size of the structure of the tracks, frame 54 and moving element 57.

The two wheels 22 and 23 are equipped with the gear arrangement to be described

presently in exactly the same way and in order to afford more clearness of description, only one side of the basket will be described, although it will be understood that the two sides are provided with exactly the same arrangement, which coact one with the other. The wheel 22 is rigidly connected to a gear 185 which may be held rigidly thereto through any suitable means such as a collar or sleeve which would be formed integral with the wheel and gear or on which the wheel and the gear would be keyed.

In this arrangement the pintles on which the wheels and gears 185 are mounted are carried by a frame 186 having a rhombus-shaped extension 187. Mounted on the upper vertex of the rhombus is a gear 188 which is rigidly connected to the basket through being bolted or riveted to a band 189 surrounding the basket or at the crossing thereof, to cross bands connecting frames 20 and 21, of the basket, or through any suitable means, properly focusing the basket for rotation.

The gears 185 and 188 are connected by intermediate gears 190 and 191 loosely journaled on pintles carried by the two free vertices of the rhombus 187.

It will be obvious that by means of this arrangement, when the basket is to be dumped by means of the operation of the pushing element 57, the gear 185 will be rotated with the wheel 22 and this transmits motion to the intermediate gears 190 and 191 which are in mesh with the gear 188 securely fastened to the basket 19, the said basket will be rotated and dumped more quickly and in a shorter space than it would be if the wheels were used alone as shown in Figure 1.

In Figure 35 also the conveyors 108 and 109 have been shown in raised position with the group of gears 112, 113 and 114 up at the highest point on the arcuate rack 124, and this shows one of the positions assumed by the conveyors and the group of gears on the operation of the controlling device shown in Figure 24 of the drawings.

As many changes could be made in the above construction, and many apparently widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. A grain shucker comprising a platform, tracks extending rearward of the platform, a basket, wheels supporting the basket and engaging with the tracks, means for rotating the basket rearwardly to the

ends of the tracks in order to dump the basket.

2. A grain shucker comprising a platform, upper and lower tracks extending rearward of the platform, a basket, wheels supporting the basket, rollers carried adjacent to the wheels, the wheels being designed to engage the lower tracks and the rollers the upper tracks, means for rotating the basket rearwardly to the end of the track in order to dump the basket. 75

3. A grain shucker comprising a platform, a frame with upper and lower tracks extending rearward of the platform, a basket, wheels formed with hubs and supporting the basket and engaging with the lower track, pintles on the wheels, rollers on the pintles engaging with the upper tracks, means for rotating the basket rearwardly to the end of the tracks, in order to dump the basket. 80

4. A grain shucker comprising a platform, tracks extending rearward of the platform, a basket, supporting frames for the basket, wheels supporting the frames and engaging with the tracks, means for rotating the basket rearwardly to the end of the tracks, in order to dump the basket. 85

5. A grain shucker comprising a platform, tracks extending rearward of the platform, supporting frames in spaced relation to each other, wheels carrying the frames and engaging the tracks, a basket rotably mounted in the supporting frames, means for rotating the basket and supporting frames rearwardly of the tracks, in order to dump the basket. 95

6. A grain shucker comprising a platform, a basket supported by the platform, tracks extending rearward of the basket, supporting means for the basket engaging the tracks, and a gear on the basket, a gear meshing with the said gear, a toothed race on top of the second gear, a pinion meshing with the race, a shaft carrying the pinion, a clutch connection on the shaft comprising two clutch members, and means to intermittently bring the two clutch members together as and for the purpose specified. 105

7. A grain shucker comprising a platform, a bracket, a basket, tracks extending rearward of the basket, supporting means for the basket engaging the tracks, a gear on the basket, a gear meshing with the said gear, a finger on the second gear, means for rotating the second gear, a lever co-acting with the said finger and means co-operating with the lever to turn the basket, as and for the purpose specified. 115

8. A grain shucker comprising a platform, a basket supported by the platform, a moving element slidably mounted rearwardly of the platform, a pivotally mounted bale on the basket, a rod on the moving element engaging the bale, a toothed race inwardly of the moving element, a transverse shaft, a 120

130

gear on the shaft engaging the toothed race, and means to actuate the shaft for moving the element to move the basket rearwardly into dumping position.

5 9. The grain shocker claimed in claim 8, in which a second race is provided in the moving element toothed concentric to the toothed race and a friction roller on the moving element on the transverse shaft to 10 engage with the second race.

10 10. A grain shocker comprising a frame, a basket supported by the frame, a supporting member provided forwardly of the basket, a moving element slidably mounted 15 on the supporting member, a pivotally mounted bale on the basket, a rod on the moving element engaging the bale, a toothed race inwardly of the moving element, a transverse shaft, a gear on the shaft engaging the toothed race and means to actuate the shaft for moving the element to move the basket rearwardly to dumping position.

20 11. A grain shocker comprising a platform, a basket supported on the platform, a moving element engaging the basket, a transverse shaft, a pinion on the shaft, a toothed race in the element engaged by the pinion, a clutch member on the shaft, a driving shaft in alignment with the trans- 25 verse shaft, a second clutch member on the driving shaft resilient and means to hold the clutch members in engagement means to release the clutch members.

30 12. A grain shocker comprising a platform, a basket supported by the platform, a gear on the basket, a gear meshing with the said gear and a finger on the second said gear, a supporting member provided forwardly of the basket, a moving element slidably mounted in the supporting member, a transverse shaft, means on the shaft to actuate the moving element, a shaft in alignment with the transverse shaft, a spring pressed 35 clutch between the shafts, a yoke connected to said clutch, and means connecting the yoke and co-acting with the finger on the gear to control the clutch.

40 13. The grain shocker as claimed in claim 12 in which the means connecting the yoke and co-acting with the finger on the gear to control the clutch comprising a flexible member connected to the yoke, a lever pivoted to the supporting member and connected at its upper end with the flexible member, 45 and a flexible member a pivot rod connected to the lower end of the lever and fastened to the pivot rod co-acting with the finger on the gear.

50 14. A grain shocker comprising a platform, tracks extending rearward of the platform, a basket, wheels supporting the basket and engaged with the tracks, a bale on the basket, a yoke engaging with the bale, means 55 controlling the movements of the yoke to

engage or release the bale, and means co- 65 acting with the said means for dumping the basket.

15. The grain shocker claimed in claim 12, in which the supporting member is provided with a bumping member to coact with 70 the moving element, as and for the purpose specified.

16. A grain shocker comprising a platform, a basket, tracks, means to move the basket to the end of the tracks, a conveyor 75 to convey the sheaves to the basket, a funnel shaped device carried by the conveyor designed to guide the fall of each sheaf into the basket, an L-shaped frame pivotally mounted on the funnel device and a covering member for the funnel device extending within the L-shaped frame, as and for the purpose specified.

17. A grain shocker comprising a platform, a basket, tracks, means to move the basket to the end of the tracks, a conveyor 85 to convey the sheaves to the basket, and means to raise the conveyor or lower the same.

18. A grain shocker comprising a platform, a basket, tracks, means to move the basket to the end of the tracks, a conveyor to convey the sheaves to the basket, an arcuate rack at the foot of the conveyor, a crank shaft for the conveyor, and a pinion 95 rigidly mounted on the crank shaft engaging the arcuate rack.

19. A grain shocker comprising a platform, a basket, tracks, means to move the basket to the end of the tracks, an elevator 100 to convey the sheaves to the basket, an arcuate rack at the foot of the elevator, a crank shaft for the elevator, a pinion rigidly mounted on the crank shaft engaging the arcuate rack, and resilient means coacting 105 with the shaft to keep the pinion in engagement with the rack.

20. A grain shocker comprising a platform, a basket, tracks, means to move the basket to the end of the tracks, an elevator 110 to convey the sheaves to the basket, an arcuate rack at the foot of the elevator, a crank shaft for the elevator, a pinion rigidly mounted on the crank shaft engaging the arcuate rack, resilient means coacting with 115 the shaft to keep the pinion in engagement with the rack, and means to lock the pinion in position on the rack.

21. A grain shocker comprising a platform, a basket, tracks, means to move the basket to the end of the tracks, a conveyor to convey the sheaves to the basket, an arcuate rack for the conveyor, a crank shaft for the conveyor, a pinion rigidly mounted 120 on the crank shaft engaging the arcuate rack, a pivoted dog designed to lock the pinion on the rack, an arcuate arm extending over the crank shaft, a flexible element con- 125

nected to the dog, and means coacting with the flexible element to operate the dog, as and for the purpose specified.

22. A grain shocker comprising a platform, a basket, tracks extending rearward of the platform, wheels supporting the basket and engaging with the tracks, means for rotating the wheels rearwardly to carry the basket to the end of the track, to dumping 10 position, and a grain collecting pan underneath the basket.

23. A grain shocker comprising a platform, a basket, tracks extending rearward of the platform and basket, wheels supporting 15 the basket and engaging with the tracks, means for rotating the basket to the end of the tracks, a conveyor to convey the sheaves to the basket, a channel member to engage the sheaves and deliver them to the basket, 20 an L-shaped frame provided with arms and carried on the channel member, a covering sheet member extending within the same, and means on the L-shaped frame whereby the same will pivot upwardly on one of said 25 arms being hit by the basket and downwardly when the basket hits the other arm on its return trip.

24. The grain shocker claimed in claim 21, in which each of the racks is formed 30 with a side groove and an under groove, a frame carrying the pivoted dog, a sliding element on the frame engaging the side groove, and a guide wheel on the frame travelling in the under groove.

35. 25. A grain shocker comprising a platform, a basket, tracks, means to move the basket to the end of the tracks, an elevator to convey the sheaves to the basket, an arcuate rack at the foot of the elevator hav-

ing a side and an under groove, a crank 40 shaft, a sleeve loose on the crank shaft, carrying gears actuating the elevators, a pinion rigidly mounted on the crank shaft engaging 45 the rack, resilient means coacting with the shaft to keep the pinion in engagement with the rack, and means to lock the pinion in position on the rack.

26. A grain shocker comprising a platform, tracks extending rearwardly of the platform, a basket, supporting frames for 50 the basket, wheels supporting the frames and engaging with the tracks, means for rotating the basket rearwardly to the end of the track to dump the basket, and a set of gears designed to coact with the last said 55 means.

27. A grain shocker comprising a platform, tracks extending rearwardly of the platform, a basket, supporting frames for 60 the basket, wheels supporting the frames, and engaging the tracks, a gear secured to each of the wheels, gears secured to the basket, gears on the frames meshing with the 65 said gears to dump the basket, and means for rotating the basket rearwardly to the end of the track.

28. A grain shocker comprising a platform, a basket supported by the platform, a moving element slidably mounted forwardly of the basket on the platform, a pivotally 70 mounted bale on the basket, a means to engage the moving element with the bale, a transverse shaft, and means to actuate the 75 shaft for moving the element to move the basket rearwardly into dumping position.

In witness whereof I have hereunto set my hand.

FREDERICK WILLIAM VARLEY.
